UNITED STATES PATENT OFFICE.

JAMES K. GARSON, OF PITTSBURG, PENNSYLVANIA.

TROUSERS-STRETCHER.

SPECIFICATION forming part of Letters Patent No. 434,129, dated August 12, 1890.

Application filed December 20, 1889. Serial No. 334,385. (No model.)

To all whom it may concern:

Be it known that I, JAMES K. GARSON, a citizen of the United States, residing at Pittsburgh, in the county of Allegheny and State of

5 Pennsylvania, have invented a new and useful Trouser-Stretcher; and I do hereby declare that the following is a full, clear, and exact description of the invention, which will enable others skilled in the art to which it appertains 10 to make and use the same, reference being had to the accompanying drawings, which form a part of this specification.

Heretofore trousers-stretchers have been constructed to apply a straight longitudinal 15 or a lateral strain on the fabric to remove the "knee-print," which is caused by overstraining the front of the leg and crimping or wrinkling the rear thereof, said straight longitudinal or lateral strain producing a straight 20 trouser-leg. When trousers are finished and pressed by the tailor, they are given a curved form, the lower ends of the legs being curved forward to cause the same to fit the calf of the wearer's leg snugly, the degree or abruptness 25 of this curve being determined by the shape of the wearer's leg and by the prevailing style. After trousers are worn for a time the front sides of the legs become strained or stretched and the rear sides thereof become wrinkled, 30 thereby giving the legs a rearward curve toward the bottom or a curve in the reverse direction to that given by the tailor. Now, if a weight or a strain is applied to the opposite ends of the leg, the rear side will be stretched 35 or strained more than the front side, and the leg will eventually become straight, and so if a stretcher consisting of two straight bars is inserted in the leg and forced apart a lateral strain is put upon the fabric, which will 40 cause the leg to become straight; but straight trouser-legs do not fit the wearer as snugly as those which are curved forward toward the bottoms.

Therefore the object of my invention is to 45 provide a simple, cheap, and effective device which will so stretch the legs of trousers as to return them to the form originally given them by the tailor, and thereby cause them to fit the legs of the wearer snugly at all 50 times.

The invention consists in a certain novel construction and combination of devices,

which are fully described hereinafter in connection with the accompanying drawings, and specifically pointed out in the appended 55 claims.

In the drawings, Figure 1 illustrates a trouser-leg as seen after it has been worn and stretched in front to form a knee-print. Fig. 2 illustrates the same as seen when finished by the tailor, and showing in dotted lines the improved stretcher arranged therein in the operative position. Fig. 3 is a view of the stretcher removed from the trousers. Fig. 4 is a perspective view of the upper end 65 of the stretcher, showing the means for adjusting the flexible band and the means for altering the curvature of the forming-bar. Fig. 5 is a similar view showing different means for adjusting the flexible band, and 70 Fig. 6 is a perspective view of the clasp at the bottom of the spring-bar.

My improved stretcher is provided with an elastic or spring bar A, which is bent or curved to conform to the shape of the rear 75 side of the leg of the trousers, as shown in Fig. 2, and is held in the desired position or shape by an adjusting rod, wire, or cord B, which is connected at its ends to set-screws b b', located near and screwed into the curved 80 bar. Thus, the adjusting rod, wire, or cord forms the chord of the arc formed by the bar, and by shortening the former the latter may be curved or bent to a greater degree, and by lengthening the former the latter is allowed 85 to straighten. In this way the curved bar may be arranged to fit snugly in the rear side of any trouser-leg.

In order to permit of the ready adjustment of the cord B, the upper set-screw b may be 90 inserted in any of the perforations b'' b'', which are formed in the bar A near its upper end. If desirable, the lower set-screw b' may also be adjustable, so as to enable the cord to be taken up at both or either end. To the 95 upper and lower ends of this curved bar are attached, respectively, the adjustable slides C D, the arms c d of the said slides being secured rigidly to the extremities of the curved bar, while the other arms c' d' thereof are 100 slotted and slide on the outer faces of the arms c d, respectively. Thumb-screws C' D' extend through the slots c'' d'' in the arms c' d' and screw into suitable perforations or

sockets in the arms *c d*, respectively, thereby enabling the independent arms of the slides to be clamped at any desired extension. A flexible band, of webbing or any other suitable material, is affixed permanently at its lower end to the free end of the arm *d'* of the lower slide and the upper end of said band, which is shown in the drawings at *E*, is adjustably connected to the upper slide. Preferably the upper end of the flexible band is slotted longitudinally, as seen at *e*, this slot fitting over the upper thumb-screw *C'*, and a yoke or transverse clamping-bar *F*, which is carried by the said thumb-screw, bears on the upper surface of the flexible band and presses it firmly against the upper surface of the slide, whereby when the arms of the slide are clamped in the desired position the flexible band is also clamped. This means for securing the free end of the flexible band is shown in Figs. 3 and 4; but in Fig. 5 is shown a somewhat simpler form, which consists, merely, in securing a buckle *F* to the arm *c'* of the slide and engaging the band therein.

25 I do not desire to limit myself to either of the above means of fastening the free end of the flexible band, as any ordinary device by which the said band may be tightened can be used. Small triangular braces *G G* are fitted in the angles between the ends of the curved bar and the stationary arms of the slides to prevent straining of the joints.

From the above description it will be observed that the essential features of my improved stretcher are the curved bar, which fits snugly in and conforms to the rear side of the leg of the trousers, and the flexible band, which bears with a firm but yielding force against the front side of the said leg and holds the garment firmly in position on the curved bar, the adjustable brace *B*, which may consist of a rod, wire, or cord, being lengthened or shortened to give the proper curvature to the bar *A* to fit the particular garment to which it is applied. The curved bar may, if the stretcher is only designed to be applied to a set of garments having the same curvature, be made of rigid or non-elastic material; but it is preferably made of an elastic material—such as wood, metal, or the like—thereby adapting it to be arranged at any desired curvature.

To apply the improved stretcher to a garment, the thumb-screws *C' D'* are loosened, so as to reduce the length of the slides, and after the curved bar is adjusted to the proper curvature the stretcher is placed in the leg of the trousers. The lower slide is extended to fit the lower end of the leg and is clamped in that position. The upper slide is similarly extended to fit in the top of the leg, and the flexible band is tightened sufficiently to draw the rear side of the leg firmly against the curved bar. In this position the flexible band exerts a constant strain on the leg of the trousers, which stretches the rear side thereof to compensate for the undue stretching which

the front side received when in use. This stretching not only smooths out all wrinkles in the rear side of the leg, but also stretches the material slightly to correspond with the stretching which the front side received by the bending of the knee of the wearer. Thus, when the garment is removed from the stretcher, it is in the shape shown in Fig. 2, which is the same shape in which it left the tailor's hands, and therefore the same snug fit is attained as when the garment was new.

When the garment is on the stretcher, the front side of the leg is not stretched, all the strain coming upon the rear side thereof, and to prevent the leg from creeping up on the curved bar or shrinking, I find it desirable to attach two small spring-clamps *G' G'*, of any ordinary or preferred form, to the bar *A* near its extremities. When these clamps are engaged with the leg of the trousers, they hold it firmly in position and enable the stretching to be accomplished quickly and satisfactorily.

Having thus described my invention, what I claim, and desire to secure by Letters Patent of the United States, is—

1. A trousers-stretcher having a spring-bar provided with laterally-adjustable end pieces, a brace connected to said spring-bar, and a flexible band connected at its ends to the extremities of the end pieces, substantially as specified.

2. A trousers-stretcher having a spring-bar provided with laterally-adjustable end pieces, a brace connected at its ends to set-screws near the extremities of the spring-bar, one of said screws being adjustable, and a flexible band connected at its ends to the extremities of the end pieces, substantially as and for the purpose specified.

3. In a trousers-stretcher, the combination, with a curved bar to fit and conform to the rear side of the leg of trousers and provided with laterally-adjustable end pieces, of a flexible band permanently connected at one end to one end piece of the said bar and adjustably connected at the other end to the corresponding end piece of the bar, substantially as set forth.

4. In a trousers-stretcher, the combination, with a curved bar to fit the rear side of the leg of trousers, of adjustable slides connected to the extremities of said curved bar and adapted to fit in the upper and lower ends of the said leg, and a flexible band affixed at its ends to the said slides, substantially as specified.

5. A trousers-stretcher having a curved bar, adjustable slotted slides attached to the ends of said bar and provided with thumb-screws to clamp their members in the desired position, and a flexible band secured at one end to one of the slides and clamped at the other end by the thumb-screw on the other slide, substantially as specified.

6. A trousers-stretcher having a curved bar, the adjustable slides having permanent arms secured to the extremities of said curved

bar and slotted arms sliding on the permanent arms, the thumb-screws passing through the slotted arms and engaging the permanent arms to clamp the same together, and
5 the flexible band secured at one end to the sliding arm of one of the slides and provided at the other end with a slot to receive the thumb-screw of the other slide, said thumb-screw being provided with a yoke or

clamping-bar to engage the said band, substantially as specified.

In testimony whereof I affix my signature in presence of two witnesses.

JAMES K. GARSON.
